UNITED STATES PATENT OFFICE.

NIELS NIELSEN, OF LINCOLN, NEBRASKA.

INSECT TRAP.

Application filed December 7, 1923. Serial No. 679,176.

To all whom it may concern:

Be it known that NIELS NIELSEN, citizen of the United States, residing at Lincoln, in the county of Lancaster and State of Nebraska, has invented certain new and useful Improvements in Insect Traps, of which the following is a specification.

The invention relates to insect traps, and has for its object to provide a device of this character comprising a cup shaped member for the reception of a liquid, preferably a poison, which cup shaped member is provided with a shank terminating in a plate adapted to be secured to an article of furniture, for instance an ice box or kitchen cabinet for forming a barrier, and preventing insects from entering the ice box or cabinet. The poison may be of any kind, however it is preferably of a character which will kill insects.

A further object is to provide the under side of the cup with a convexed surface, which will easily slide over the floor and act as a caster.

25 A further object is to provide the shank of the device with a chamber in communication with the chamber of the cup shaped member, thereby allowing the reception of the maximum amount of liquid to a minimum size cup, and preventing rapid emptying of the cup incident to evaporation.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit 40 of the invention.

In the drawings:—

Figure 1 is a perspective view of the device, showing a plate carried thereby, whereby the device may be easily attached to bottom of a piece of furniture.

Figure 2 is a vertical transverse sectional view through the device.

Referring to the drawing, the numeral 1 designates an elongated plate adapted to be secured to a piece of furniture by means of

screws or the like, which may be passed through the apertures 2. Extending downwardly from the plate 1 is a hollow shank 3, which shank extends axially into the chamber 4 of the substantially semispherical cup 5. The shank 3 is preferably formed integral with the plate 1 and the cup 5, thereby allowing the device to be cast from a single piece of material. By forming the cup 5 semi-spherical, the convexed end 6, thereof which rests on the floor will easily slide over the floor and act as a caster. Shank 3 is provided with a chamber 7, which chamber at its lower end is in communication with the chamber 4 through apertures 8, and consequently when the poison liquid 9 is placed in the cup 5, the chamber 7 will be filled, thereby allowing the reception of the maximum amount of liquid in the minimum sized cup, consequently the cup will not be of a size where it will detract from the artistic appearance of the piece of furniture on which the device is applied, at the same time the cup will not become empty incident to evaporation as it would if the chamber 7 in the tank 3 were not provided. The shank 3 adjacent its upper end is provided with a vent opening 10, which opening allows the escape of air, consequently the liquid within the chamber 7 may easily flow into the same or out as the liquid is consumed incident to evaporation.

The invention having been set forth what is claimed as new and useful is:—

An insect trap adapted to support a piece of furniture, said trap comprising a plate adapted to be secured to a piece of furniture, a shank carried by said plate and having a chamber therein, a cup into which the lower end of said shank extends axially and adapted to receive liquid in a chamber thereof, which chamber is in communication with the chamber of the shank, the lower end of said cup being convexed, thereby forming a caster and a vent in said shank adjacent its upper end and in communication with the chamber of the shank.

In testimony whereof I affix my signature.

NIELS NIELSEN.
